UNITED STATES PATENT OFFICE.

FRED POOLE, OF JEWELL, KANSAS.

WATER-HEATER.

1,326,964.

Specification of Letters Patent.

Patented Jan. 6, 1920.

Application filed February 9, 1915. Serial No. 7,172.

To all whom it may concern:

Be it known that I, FRED POOLE, a citizen of the United States, residing at Jewell, in the county of Jewell and State of Kansas, have invented certain new and useful Improvements in Water-Heaters, of which the following is a specification.

This invention relates to water heaters, and more particularly to that class of water heaters commonly termed instantaneous, and the structure illustrated in this application serves to set forth one of the several applications of my improvement.

The primary object of the present invention is to provide a form of instantaneous water heater which may be inserted in a water conduit at any desired point and in a manner which will least interfere with the passage of water through the conduit.

Another object of the present invention is to provide a water heater of the above-mentioned class which affords a relatively large heating area, thereby tending toward a more rapid heating of the liquid coming in contact therewith.

A still further object of the present invention is to afford suitable means for supporting the above-mentioned structure within a water conduit, and to associate with said supporting structure an improved circuit connecting plug.

With the above and other objects in view my invention resides preferably in the construction, combination, and arrangement of parts as hereinafter set forth in the specification and illustrated in the accompanying drawings, in which—

Figure 1 is a side elevation of my invention showing its application to a water conduit or the like, the conduit being broken away.

Fig. 2 is a longitudinal sectional view of my invention, the connecting plug being shown in elevation.

Fig. 3 is a vertical sectional view through a portion of a water conduit and heater showing my improved connecting plug in vertical section.

Similar reference characters indicate similar parts throughout the various views of the drawings.

Referring more particularly to the drawing in which the preferred embodiment of my invention is illustrated, the numeral 1 indicates a water or similar conduit of any

of the usual types, the portion 1 being detachably interposed in the main portion 2 by means of a connecting nut 3.

My improved heater preferably comprises a pair of parallel tubular arms or casings 4 and 5 longitudinally disposed in said conduit 1 and spaced from the walls thereof, as will be more fully set forth hereinafter. The respective ends of the parallel tubular arms 4 and 5 are connected by means of arcuate tubular members 6 and 7, the respective ends of the tubular members 6 and 7 being in threaded or other suitable engagement with the respective ends of the tubular members 4 and 5 as indicated at 8 to provide a substantially elliptically-shaped structure. The inner surfaces of the tubular members 4, 5, 6 and 7 are preferably lined with some insulating material such as asbestos as shown at 9, the said insulating material being broken at 10 adjacent the points at which the sections 4, 5, 6, and 7 are joined. A resistance element of any suitable design is receivable within the tubular members 4, 5, 6, and 7 and is diagrammatically indicated, the numeral 11 designating this heating element.

Any suitable means may be employed for supporting the elliptical structure in spaced relation to the walls of the conduit 1, but I have illustrated a T-coupling which is provided with a nipple portion 12 which has its respective ends 13 and 14 connected to the tubular arm 5, the said tubular arm being divided at any desirable point for threaded engagement or the like with the said nipple 12. The said portion 12 is provided with a right-angularly extending portion 15 which is secured to the conduit 1 as shown at 16 in Fig. 2 in any suitable manner, the said right-angularly extending portion 15 being tubular and serving to act as an electric conduit for reception of electrical conductors of any type, connection being had with a source of electric energy in any suitable manner, a preferred manner being set forth herein-after.

In order to assemble the parts of the closed-loop pipe, the sectional casing 5 is placed to have its ends bearing against the nipple portion 12, while the casing 4 is positioned parallel to the sectional casing 5. The arcuate tubular members 6 and 7 are then placed to have their ends bearing upon the ends of the sections 4 and 5. Simultaneous rotation of the sections 4 and 5 will 110

cause their ends to be screwed into the nipple 12 and the arcuate tubular members 6 and 7, thus assembling this closed-loop pipe.

It will be seen from the above description 5 that I have provided a heating element which is readily receivable within a conduit, provides a large heating area and at the same time does not interfere in any substantial manner with communication through 10 the conduit.

Any approved form of electrical connecting plug may be used for supplying electrical energy to the heating element, but I have illustrated a preferred form in Fig. 3 15 of the drawing, wherein the conduit or the like is indicated by the numeral 1, as above, and is provided with a threaded opening 17. An externally threaded tubular bushing 18 is receivable within the opening 17 and is 20 locked therein by means of a spacing nut 19 and the gripping nut 20. The inner end of a bushing 18 is securely locked in the casing 5 in any of the many forms of heating elements which I provide, the said bushing 18 25 being in screw-threaded engagement with the said casing 5 as indicated at 22. An insulating locking washer 23 is threaded on the bushing 18 at the time of its insertion into the casing 5 for the purpose of preventing 30 accidental movement thereof. A protecting ring 24 surrounds the gripping nut 20 and is securely supported on the casing 1 by means of bolts 25, the said bolts 25 forming circuit terminals for electrical conductors 26, the terminals of said conductors 35 26 being received on the bolts 25, and securely held in position thereon by means of lock nuts 27, the circuit terminals proper comprising two split arms 28 having right- 40 angular portions 29 for engagement with the bolts 25. A plug 30 of any insulating material is provided having diverging communicating apertures 31 therein, said apertures 31 having the respective wires 32 of an 45 electric circuit carried therein, the terminals of said electric conductors 32 being in electrical communication with tubular members 33 open at their upper ends into which are receivable the divided arms 28. The di- 50 vided arms 28 are somewhat springy in nature and will retain the coupling plug 30 thereon when the same is forced into position by insertion of the arms 28 into the complementary tubular members 33, thereby 55 completing a circuit to the heating element carried in the casing 5. As illustrated clearly in Fig. 3, it will be noted that the bolts 25 are provided with insulating sleeves 25' while the conductors 26 are insulated 60 from the lower end of the bushing 18 and from the gripping nut 20 as well as the ring 24, by the insulating washer 26'.

The electrical conductors 26 are retained in spaced relation to the walls of the bushing 18 and each other by means of an insulating material 26' of any approved type, a cement being indicated.

While I have shown and described the above form of my invention as possessing a peculiar form and construction, it is desired that it be understood that I may make such changes in the details thereof that do not depart from the spirit and scope of the invention as claimed.

Having thus described my invention what 75 I claim and desire to secure by Letters Patent, is:

1. In a water heater, the combination with a conduit, of a substantially elliptical tubular heating body disposed in the conduit, means arranged on the conduit for facilitating the mounting and removal of the heating body therewithin, an electrical resistance element within the tubular body, an asbestos covering for the element, a coupling member for the tubular body, binding connections having an insulated channel for supporting the tubular body in the conduit, electrical connections passing through the insulated channels and joined with the resistance element, and spring terminals for the electrical connections.

2. In a water heater, the combination of a conduit, a tube consisting of a plurality of sections interposed within said conduit, heating means within said tube, a locking washer positioned in said tube, a spacing nut positioned between said tube and said conduit, a gripping nut positioned upon the exterior of said conduit, an externally threaded bushing projecting through said conduit and one section of said tube engaging said locking washer, said spacing nut and said gripping nut, thus causing the nut and bushing to space said tube and conduit apart and also forming a liquid tight joint, a protector ring bearing upon said conduit and being positioned about said gripping nut, bolts projecting through said conduit and said protector ring and being insulated therefrom, conductors projecting through said bushing and being insulated therefrom and having their ends supported by said bolts, arms supported by said bolts in contact with said conductors, and means 105 removably connected to said arms for forming a circuit.

In testimony whereof I affix my signature in presence of two witnesses.

FRED POOLE.
